ROLLER SKATE HAVING UNITARY PLASTIC BODY

Charles E. Jones, Chicago, and William G. Crowle, Berwyn, Ill., assignors to Manning Manufacturing Corporation, Chicago, Ill., a corporation of Illinois

Application July 26, 1956, Serial No. 600,218

6 Claims. (Cl. 280—11.26)

The invention relates to improvements in roller skates and is more particularly concerned with the novel construction and assembly of the various components thereof.

The skate embodying the features of the present invention is fabricated for the most part from tough nylon plastic or other suitable wear resisting moldable plastic material. The skate consists of a minimum of parts all of which are easily and quickly assembled in such manner that the skate may be adjusted readily through a range of sizes within the physical limits of its construction. More particularly, the skate includes a heel portion and a toe portion, each of which is molded and reinforced to withstand considerable abuse to which such parts are ordinarily subjected. Each such portion also has molded or otherwise formed integral therewith, a journal boss in which is mounted an axle for a pair of wheels of novel construction. The two skate portions are joined for size adjustment toward and away from each other by a bridging channel or bar which is slideably guided in each portion and has means associated with it and with said portions to secure said portions thereto in any selected position of adjustment. Furthermore, the channel or bar member is preferably of metal and it is so associated with the portions as to coact with the journal bosses to reinforce the structure and thus further strengthen the molded plastic portions.

The skate disclosed herein is further characterized by having novel means embodied therein to accommodate and mount ankle and toe straps and by the inclusion of a novel toe strap having means therein to coact with the toe portion of the skate to facilitate its ready mounting. Also, the skate has novel nylon bearing means for the wheels.

It is therefore one of the objects of the present invention to provide a rugged novelly constructed roller skate of the kind described.

Another object is to provide a skate with novelly constructed molded heel and toe portions having integral journal bosses.

Another object is to provide a skate of the character described with means connecting the heel and toe portions for adjustment which functions to reinforce the said portions and the integral journal bosses.

Another object is to provide novelly constructed journal bosses.

Another object is to provide a novel construction for mounting a wheel on an axle.

Another object is to provide a novel toe strap and novel means mounting it detachably on a skate.

With the foregoing and such other objects in view, which will appear as the description proceeds, the invention consists of certain novel features of construction, arrangement and combination of parts hereinafter fully described, illustrated in the accompanying drawings, and particularly pointed out in the appended claims, it being understood that various changes in form, proportion, size and

2

minor details of the structure may be made without departing from the spirit of the invention.

Referring to the drawings in which the same characters of reference are employed to identify corresponding parts:

Fig. 1 is a plan view of a roller skate embodying the invention.

Fig. 2 is an inverted plan view.

Fig. 3 is a longitudinal vertical sectional view taken on line 3—3 of Fig. 1.

Fig. 4 is a transverse sectional view taken on line 4—4 of Fig. 3.

Fig. 5 is a fragmentary side elevational view of the front end of the toe portion.

Fig. 6 is a plan view of the toe strap.

Referring to the accompanying drawings, the roller skate illustrated comprises a heel portion 5 and a toe portion 6 connected for adjustment, as to skate size, by a bridging bar or channel 7. Each of the portions 5 and 6 is fabricated from suitable moldable material such as nylon plastic so as to be very durable and wear resisting while maintaining a sufficient amount of resiliency to resist breakage, chipping, etc.

As illustrated, the heel portion 5 is fabricated in one piece and it includes a top wall 8 having an upstanding arcuate heel stop 9 formed of two material thicknesses 9a—9b with a space 10 therebetween which opens into a slot 11 on each end. The outer or rearmost wall 9b depends below the top wall 8 and it merges at its ends below the slots 11 in side flanges 12 that depend from the wall 8. Also formed integral with the top wall 8 are a pair of laterally spaced parallel webs 13 defining an inverted longitudinal recess 14 between them that opens onto the forward edge of the heel portion 5. A journal boss 15 is formed integral with the heel portion 5 and, as shown, this boss depends from the bottom face of the top wall 8 and has parallel end walls 16 and downwardly converging front and back walls 17 and 18 respectively.

As illustrated, the end walls 16 of the journal boss 15 are integral with the spaced webs 13 and the front and back walls 17 and 18 terminate substantially in the plane of the bottom edges of the webs 13 so as to leave between the upper edges of said walls 17 and 18 and the bottom surface of the top wall 8 aligned openings 19 in register with the inverted longitudinal recess 14 between the webs 13. It should be observed that the end walls 16 are spaced inwardly slightly from each related web 13 so as to provide in the space thereabove, a pair of shoulders 20 for a purpose to be made apparent presently. The journal boss 15 provides a mounting for a pair of back wheels 21. In order to permit the entire heel portion to be molded or cast in one piece, the journal boss is made hollow as shown and with its core opening 22 in the top wall 8.

The toe portion 6 also is fabricated of the same material and in a manner similar to the heel portion. The portion 6 includes a top wall 23 having a surrounding downwardly extending flange 24 and a pair of longitudinally extending spaced parallel webs 25 on its bottom face. The webs 25 define an inverted longitudinal recess 26 between them that opens onto the rearwardly disposed edge of the toe portion. The toe portion 6 also carries an integral hollow journal boss 27 that is similar to the boss 15 on the heel portion and it includes end walls 28 and converging front and back walls 29—30. In this instance however, the front wall 29 extends to and is integral with the top wall 23 thus affording a three wall connection between said boss and said top wall. The end walls 28 are offset inwardly from the connected webs 25 so as to define upwardly facing internal shoulders 31 for a purpose to be explained presently. The journal

boss 27 provides a mounting for a pair of front wheels 21.

As noted hereinabove, the heel portion and the toe portion are connected together for longitudinal adjustment toward and away from each other by a bridging bar or channel 7. The channel 7 is fabricated from sheet metal stock and it is of a width to fit snugly into the longitudinal recesses 14-26 between the pairs of webs 13-25 on the respective portions 5 and 6. The side flanges of the channel are of a depth to fit snugly between the bottom surface of the top walls 8 and 23 and the related shoulders 20-31 so as to thereby absorb some of the stress imposed upon the journal bosses 15 and 27 and the webs 13 and 25, to which they are connected.

Each portion 5 and 6 of the skate has a substantially square recess 32 in its top wall with a central aperture 33 therein to receive the square head and threaded shank of a bolt 34 that projects through a slot 35 in the related end of the bar or channel 7. A washer 36 and wing nut 37 mounted on the shank of each bolt affords means for securing the skate portions 5 and 6 and channel 7 adjusted relative to each other.

Each journal boss 15-27 has mounted therein, an axle 38. As is best shown in Fig. 4, the axle has knurled end portions that project out through the end wall of the boss and have press-fitted thereon, nylon bearings 39 that are externally flanged, as at 41. Prior to press-fitting the bearings 39 onto the axle ends, a wheel 21 is fitted over the bearings 39. In this manner the wheels 21 are mounted for free rotation on the bearings 39 and are retained against axial shifting by the flange 41 on one side and by the boss on its other side. The wheels 21 preferably are fabricated also from nylon plastic so as to be long wearing and to resist breakage, although they may be made of any other suitable material.

The skate is adapted to be held removably on the shoe of the wearer by means of an ankle strap 42 and a toe strap 43. Referring to Figs. 1 and 3, it will be observed that the ankle strap 42, which preferably is made of suitable plastic material, is threaded through the slots 11 in the ends of the double walled heel stop 9. The toe strap 43 is specially formed to be engaged detachably with the toe portion 6 in front of the journal boss 15 thereon. This strap is best shown in Fig. 6, wherein it will be observed that it includes a relatively wide medial area 43b and narrow end portions 43a, one of which carries a buckle 44 and the other of which is suitably perforated to co-act with the buckle. The wide area 43b is disposed beneath the toe portion and is cut away, as at 45, to accommodate the journal boss 15. It is also provided with laterally opposed notches 46 that are so spaced as to register with cut back recesses 47 in the side flange 24 of the toe portion (Fig. 5). This arrangement is such that the toe strap 43 may be easily and quickly snapped into and out of engagement with the recesses 47 and, when engaged, is held against displacement and loss.

As many possible embodiments may be made in the invention, and as many changes might be made in the embodiment above set forth, it is to be understood that all matters hereinbefore set forth or shown in the accompanying drawings are to be interpreted as illustrative and not in a limiting sense.

Having thus described the invention, what is claimed as new and desired to be secured by Letters Patent is:

1. A skate comprising a heel and a toe portion each having a flat top wall, said portions being arranged end to end, a pair of laterally spaced parallel longitudinal webs integral with and depending from the bottom face of each top wall, the webs on each portion defining with the respective top wall inverted channels, said channels opening onto the opposed ends of said portions, a connecting bar extending between said portions and having its ends telescoped into the channels, means to secure the bar to the top walls for adjustment of the portions relative to said bar, wheel-carrying hollow journal bosses on

each portion, said bosses each including parallel side walls integral with a respective pair of said webs, said side walls being offset inwardly of said webs to define upwardly facing longitudinal shoulders in abutment with the bar so as to transmit the load carried by the journal bosses to said bar, and a heel stop on the heel portion comprised of an upstanding wall integral with the top wall thereof and a depending wall spaced from the upstanding wall and integrally connected at its upper edge to the upper edge of the upstanding wall, said walls being arched laterally and defining an inverted channel open at each of its ends to receive an ankle strap threaded therebetween.

2. In a skate, a heel portion fabricated from moldable plastic material, said heel portion comprising a top wall having a pair of longitudinally extending laterally spaced webs on its bottom face defining with the top wall an inverted channel, said channel opening on one end of said heel portion and being adapted to slidably receive a bar, a hollow journal boss depending from and opening into the top wall, said boss including side walls one integral with each web and downwardly converging end walls, said side walls being offset inwardly of said webs to define upwardly facing longitudinal shoulders adapted to have abutment with the bar so as to transmit a part of the load carried by the journal boss to said bar, and a heel stop on the heel portion comprised of an upstanding wall integral with the top wall thereof and a depending wall spaced from the upstanding wall and integrally connected at its upper edge to the upper edge of the upstanding wall, said walls being arched laterally and defining an inverted channel open at each of its ends to receive an ankle strap threaded therebetween.

3. A skate of the character described in claim 1, in which the depending wall is substantially coextensive with the upstanding wall and is located outwardly of the upstanding wall.

4. In a skate of the character described in claim 2, in which the depending wall is substantially coextensive with the upstanding wall and is located outwardly of the upstanding wall.

5. A skate comprising a heel and a toe portion each having a flat top wall, said portions being arranged end to end, a pair of laterally spaced parallel longitudinal webs integral with and depending from the bottom face of each top wall, the webs on each portion defining with the respective top wall inverted channels, said channels opening onto the opposed ends of said portions, a connecting bar extending between said portions and having its ends telescoped into the channels, means to secure the bar to the top walls for adjustment of the portions relative to said bar, wheel-carrying hollow journal bosses on each portion, said bosses each including parallel side walls integral with a respective pair of said webs, said side walls being offset inwardly of said webs to define upwardly facing longitudinal shoulders in abutment with the bar so as to transmit the load carried by the journal bosses to said bar, and a heel stop on the heel portion comprised of an upstanding wall integral with the top wall thereof and a depending wall spaced from the upstanding wall and integrally connected at its upper edge to the upper edge of the upstanding wall, said walls being substantially coextensive to each other and defining an inverted channel open at each of its ends to receive an ankle strap threaded therebetween.

6. In a skate, a heel portion fabricated from moldable plastic material, said heel portion comprising a top wall having a pair of longitudinally extending laterally spaced webs on its bottom face defining with the top wall an inverted channel, said channel opening on one end of said heel portion and being adapted to slidably receive a bar, a hollow journal boss depending from and opening into the top wall, said boss including side walls one integral with each web and downwardly converging end walls, said side walls being offset inwardly of said webs

to define upwardly facing longitudinal shoulders adapted to have abutment with the bar so as to transmit a part of the load carried by the journal boss to said bar, and a heel stop on the heel portion comprised of an upstanding wall integral with the top wall thereof and a depending wall spaced from the upstanding wall and integrally connected at its upper edge to the upper edge of the upstanding wall, at least one of said walls being arched laterally and both of said walls defining an inverted channel open at each of its ends to receive an ankle strap threaded therebetween.
